HYDROGENATION PROCESS OF OIL
REFININGNathan J. Lockhart, Redondo, Calif., assignor to
Lathrop Investment Corporation, Los Angeles,
Calif., a corporation of California

Application July 2, 1932, Serial No. 620,669

3 Claims. (Cl. 196—62)

This invention relates to a method and apparatus for treating hydrocarbon oils by a process of hydrogenation.

In the treatment of hydrocarbon oils by the hydrogen process it is usually necessary at some stage of the process to raise the temperature of the hydrocarbons which may then be in liquid or vapor phase, to a relatively high degree of temperature, and at such times the apparatus may develop weaknesses which cause disaster. This is due to the development of leaks or the accumulation of free carbon in the system which may cause highly explosive and combustible combinations of elements to be created, resulting in fires and often endangering life and considerable property.

It is the principal object of the present invention to provide an apparatus and a method of using the same, which eliminates the possibility of undue internal pressure in the system and prevents the excessive heat from corroding, cracking, or otherwise causing the conduits to become weakened and ruptured.

The present invention contemplates the use of apparatus through which hydrocarbon oils in liquid or vapor phase may be conducted, and during which time they may be treated by apparatus including a separate vaporizing chamber in which the hydrocarbon oils are mechanically atomized, and the apparatus further including heat treating units in which the conduits are jacketed by insulation layers of molten metal which are liquid at the operating temperature of that particular piece of apparatus.

The invention is illustrated by way of example in the accompanying drawing, in which:—

Figure 1 is a view in diagram showing a flow plan of the preferred form of my apparatus.

Fig. 2 is a fragmentary view in section and elevation showing one of the atomizing nozzles used in the apparatus.

Fig. 3 is a fragmentary view in section showing the manner in which certain parts of the apparatus are jacketed by the use of molten metal as insulating walls.

Referring more particularly to the drawing, 10 indicates a tank or reservoir in which oil to be delivered is stored. This may be oil of any gravity, but it has been found that the present apparatus operates with very desirable and efficient results when treating oil ranging from that which is known commercially as from 12 to 16 gravity. A draw-off pipe 11 is connected with the reservoir 10 and communicates with the bottom of a still 12. This still is heated to the tem-

perature of approximately 500° F., by any suitable means, such as the gas or oil burner 13, during which time the oil passes from the pipe 11 into a coil 14 and then flows upwardly through the coil to an outlet pipe 15 communicating with a nozzle structure 16. This nozzle is shown in detail in Fig. 2 of the drawing, where it will be seen to comprise a tubular feed pipe 17 extending horizontally through the end wall 18 of an expansion chamber 19. This feed pipe is externally threaded at its outer end to receive the threaded shank 20 of a nozzle 21. The outer end of the nozzle member is formed with a central opening 22 through which liquid may be ejected. Mounted in fixed relation to the end of the feed tube 17 is a metal valve stem 23 which is tapered at its outer end as indicated at 24, and which end may be adjusted with relation to the opening 22 against which it may feed. This adjustment is brought about by the rotation of the nozzle structure 21 upon the threaded portion of the tube 17. This will cause the nozzle opening to advance or retract with relation to the valve stem 23. The oil in substantial liquid phase and at a temperature of approximately 500° F. will be projected into the expansion chamber 19 at which time it will be atomized and caused to expand. A pipe 25 communicates with the top of this expansion chamber and draws the hydrocarbons away in vapor phase through a pipe 26. This conduit is of relatively large diameter and conducts the hydrocarbon vapors into a heat treating unit 27. Suitable heat generators, such as the burners 28 are provided to raise the temperature of the vapors to approximately 1120° F. The conduit 26 is led into the heat unit and communicates with an upper coil 29 which is formed with convolutions extending horizontally. The length of this coil may be as desired, while the outer end of the coil extends from the heat compartment into a hydrogen mixing box 30. Disposed within the heat chamber 28 and beneath the coil 29 is a coil 31 through which steam is conducted from a boiler 32. It will thus be evident that the steam in the coil 31 will be superheated to the temperature of 1120° F. which will be the same temperature as that attained by the hydrocarbon vapors in the coil 29. The outer end of the steam coil 31 is formed with a gooseneck 33, the ejection end of which extends vertically into an accumulated bath of molten metal 34 carried in the bottom compartment 35 of the hydrogen mixing box. The steam from the coil is thus emptied into the bath of molten metal and its hydrogen content will pass off through a pipe 36 into the mixing com-

partment 37 of the hydrogen mixing box 30. Here the hydrogen will mix with the hydrocarbon vapors.

A vapor pipe 38 conducts the mixed hydrocarbon and hydrogen to the condenser 39 where these vapors will be cooled in the presence of a cooling meter, such for example, of water at the ordinary temperature of 65°. The condensate is then drawn off from the condenser through a pipe 40 and is delivered as gasoline to a suitable storage reservoir.

The manner in which the vapor and steam coils 29 and 30 are protected from the excess heat in the heat treating unit 27 is clearly shown in Fig. 3 of the drawing, where it will be seen that these elements include an outer pipe 41 separated from an inner pipe 42, the outer pipe communicating with the end wall of the compartment 35 of the hydrogen mixing box and the inner pipe 42 terminating in a gooseneck 33 previously described. The openings of the pipes are below the level of the molten metal 34 and make it possible to fill the space 44 between the outer pipes 41 and the inner pipe 43 with this molten metal which will act as a protecting and insulating jacket for the inner pipe 42, and will at the same time accumulate within the compartment 35 to form a trap for the steam ejected from the coil 31 and to permit the hydrogen to pass to the upper compartment of the mixing box.

Attention is also directed to the fact that this arrangement will permit expansion and contraction of the molten metal without placing any undue strain on the parts of the apparatus.

In operation lead has been used as the molten metal, but in actual practice any desired metal might be used just so long as it becomes molten at the operating temperature of that particular element of the device. In the particular application of the use of molten metal as an insulating device in the present instance, the drawing shows the use of concentric pipes between the spaced walls of which the molten metal is maintained. It will be understood that other forms of conduits and jackets might be used, but that this particular feature of the invention is concerned with the interposition of molten metal between the walls of a container, the outer walls of which are subjected to a high degree of heat.

In operation of the present invention it is desirable to treat relatively low gravity oil in the apparatus, since the structure acts efficiently to bring about the recovery of an unusually high percentage of gasoline. The low gravity oil is placed in the storage reservoir 10 and may be drawn therefrom as required to the still 12. Here it is heated to a temperature of substantially 500° F., and the heated material is then led into the atomizing nozzle 16. This nozzle will cause the vapor and finely divided liquid to be projected into the expansion chamber 19, and since the pressure of the fluid projected from the nozzle is relatively high as compared with the atmospheric pressure within the expansion chamber, the fluid will have opportunity to expand and vaporize. The hydrocarbon vapors then are drawn off through the pipe 26 to the upper coil 29. This coil may be jacketed as previously described, and an insulating bath of molten metal may be interposed between the conduit containing the fluid and the jacket wall. The coil 29 is in the upper part of the heated unit 27. This unit is heated by suitable burners 28 to a high degree of temperature. The temperature proposed is 1120° F. Disposed within the heat unit beneath the coil 29 is the steam

coil 31 which is jacketed as previously described. Attention is directed to the fact that steam is superheated to the same temperature as the incoming hydrocarbon vapors so that when they are led together in the hydrocarbon mixing box they will be of uniform temperature and will produce a homogeneous vapor. The superheated steam led from the boiler 32 through the coil 31 is expelled through the gooseneck 33 into the bath of molten metal 34 and as it percolates upwardly through the molten metal the hydrogen will escape through pipe 36 into the hydrogen mixing box where it will commingle with the hydrocarbon vapors expelled from the coil 29. These vapors and the hydrogen will then form a vapor which is led through pipe 38 to the condenser 39. Here condensation takes place to permit the recovered gasoline to be drawn from the condensate draw-off 40.

It will thus be seen that the device here disclosed provides simple and effective means for first producing a hydrocarbon vapor and a desired amount of hydrogen gas, and thereafter causing these two vapors to commingle in a manner to obtain a high yield of gasoline from a relatively low gravity hydrocarbon oil. And it will be further seen that the apparatus here disclosed permits the fluids to be handled without danger of carbonization due to the high heat directly delivered to the walls of the conduits, and without danger of rupture of the pipes due to intimate contact of the flames with the walls of the conduits through which the fluids are flowing.

While I have shown the preferred form of my invention, as now known to me, it will be understood that various changes may be made in combination, construction, and arrangement of parts by those skilled in the art without departing from the spirit of my invention as claimed.

Having thus described my invention, what I claim and desire to secure by Letters Patent is:—

1. In oil refining equipment, a still through which liquid hydrocarbon is passed and within which it is heated, an expansion chamber into which the heated oil is introduced by atomization, a heat unit through which the oil is conducted within a conduit and within which its temperature is raised to that of vapor phase, a steam conduit passing through said heating unit, heating means for simultaneously raising the oil and steam to substantially the same degree of temperature, a molten metal bath into which the discharge end of the steam conduit is submerged, a mixing box into which hydrogen liberated from said metal bath and the hydrocarbon from the heat unit are conducted and a condenser through which the mixture of hydrogen and hydrocarbon are passed.

2. In oil refining equipment, a still through which a liquid hydrocarbon is passed and within which it is heated, a conduit leading from the still, an expansion chamber of relatively large area into which the heated oil is delivered from the conduit, an atomizing nozzle on the conduit and through which the oil is passed to the expansion chamber, a drawoff pipe from the expansion chamber for the atomized oil, a heat pipe connected with the drawoff pipe and through which the atomized oil passes, a heat treating unit including said pipe, a mixing chamber into which the heated oil is delivered after passing through the heat treating unit, a steam pipe within the heat treating unit and communicating with a source of steam supply, heating means

for simultaneously heating the steam and the atomized oil passing through the heat treating unit, a jacket disposed around the steam pipe and which is filled with molten metal, a box in communication with said jacket and within which molten metal accumulates to a level to maintain the jacket filled at all times, a gooseneck formed on the end of the steam pipe, the lower end of which is submerged within the molten metal with-
5 in the box whereby steam from the pipe will be introduced into the molten metal and must per-
colate upwardly therethrough, a connecting pipe between the box and the mixing chamber whereby the steam will be caused to commingle with
10 the hydrocarbons within the mixing chamber, and a condenser in communication with said mixing
15

chamber and within which light hydrocarbon fractions are obtained by condensation.

3. In oil refining equipment a heat treating unit comprising an outer shell, a conduit within the upper part thereof and through which oil vapors and atomized oil pass, a compartment into which said oil products are discharged, a second compartment in communication therewith into which said oil products may pass, a steam conduit passing through the shell and communicating with said second compartment, a jacket for said conduit, said jacket surrounding the conduit and the second compartment being filled with molten metal into which steam is introduced within the second compartment.
